UNITED STATES PATENT OFFICE.

WILLIAM A. JENNINGS, OF RAYTOWN, MISSOURI.

CYLINDER-GRINDING ATTACHMENT FOR LATHES.

1,425,592.

Specification of Letters Patent. Patented Aug. 15, 1922.

Application filed May 31, 1921. Serial No. 474,035.

To all whom it may concern:

Be it known that I, WILLIAM A. JENNINGS, a citizen of the United States, and resident of Raytown, county of Jackson, 5 State of Missouri, have invented a certain new and useful Improvement in Cylinder-Grinding Attachments for Lathes, of which the following is a complete specification.

This invention relates to cylinder grinding appliances, and has for its object to produce an attachment which can be readily secured to a lathe of any approved type after removing the head-stock thereof, and by which a cylinder or other object 15 can be efficiently and accurately ground.

A further object is to produce an attachment accurately adjustable to operate on cylinders or the like of widely different diameters.

20 More specifically, the object is to produce an attachment having a grinding wheel adapted to be revolved around its own axis at a high rate of speed and to bodily describe a circle at a relatively low speed, 25 and embodying means for manual adjustment to vary the diameter of the circle described by the wheel without affecting its speed of rotation around its own axis.

With these objects in view the invention 30 consists in certain novel and useful features of construction and combinations of parts as hereinafter described and claimed; and in order that it may be fully understood reference is to be had to the accompanying 35 drawings, in which:

Figure 1 represents a side elevation of a part of a lathe equipped with a grinding attachment embodying the invention, certain parts being broken away to disclose 40 parts otherwise hidden.

Figure 2 is an enlarged central longitudinal section of parts of the apparatus shown in Figure 1.

Figure 3 is an enlarged end view of the 45 attachment, and shows in conjunction therewith a cylinder being ground.

Figure 4 is a central longitudinal section taken on the line IV—IV of Figure 3.

Figure 5 is a cross section taken on the 50 line V—V of Figure 4.

Figure 6 is a section taken on the line VI—VI of Figure 4.

Figure 7 is an enlarged section taken on the line VII—VII of Figure 5.

55 Referring now to the drawings in detail, 1 indicates a part of a lathe of any suitable

or preferred type and 2 and 3 represent bearings at the head end of the lathe. 4 represents the mandrel journaled in the bearings and 5 the customary cone pulley 60 mounted on the mandrel and adapted to be operated through the medium of a belt, (not shown), in the customary manner.

In lieu of the usual head-stock of the lathe, a threaded disc 6 is mounted on the 65 end of the mandrel, and bolted as at 7 to said disc, is a large plate 8 having a hub portion 9, the bore of which communicates with the bore of the mandrel 4. Integral with the plate 8 is a boss 10 having an 70 arcuate inner face extending concentrically with the axis of plate 8 on the mandrel, as shown clearly by Figure 3, and said plate is formed with a circular face 11 struck from the same center as the 75 arcuate face of the boss and inclined slightly with respect to the axis of the mandrel, as shown clearly by Figure 4. A retaining ring 12 fits against said inclined face and the arcuate face of the boss 10, and is bolted 80 firmly as at 13 to the plate 8, said retaining ring being recessed at 14 at its rear side for the accommodation of a large worm wheel 15 journaled in the retaining ring and fitting around the hub 9 of plate 8, it 85 being evident that as said wheel is fitted against the inclined face of the plate, the axes of the wheel and plate intersect.

The worm wheel 15 is intergeared with a worm 16 suitably journaled in the boss 90 10, which boss and the adjacent portions of the plate 8 and retaining ring 12 are recessed as at 16^a (see Figure 5) for the accommodation of said worm 16. The worm 16 is equipped with a knob 17 at 95 its outer end, and said knob is provided with a circular dial 18, any division mark of which is adapted to register with a mark 19 on the boss, the arrangement being such that the operator by noting the relation 100 between the dial marking and the mark 19, can adjust the worm wheel to the desired extent, for a purpose which hereinafter appears.

The retaining ring 12 is provided with 105 a radial marking 20 for registration with dial markings 20^a on the exposed face of the worm wheel, as shown clearly by Figure 6, and said worm wheel within the said dial marking 20^a is recessed as at 21 concentrically of the axis of the mandrel. A tubular arm 22 is provided with a circular

base flange or enlargement 22^a having an inclined face fitting snugly in the recess 21 having its bottom in a plane at an angle to the corresponding plane of the wheel 5 and is bolted rigidly in place as at 23 to the worm wheel, and secured within said arm at the outer and inner ends thereof respectively, are bearing bushings 24 and 25, and between said bushings the arm is 10 provided with a plug closed oiling opening 22^b.

A shaft 27 extends axially through said arm, but it will be apparent from the above that the axis of the shaft is at an angle to 15 that of the wheel 15, on account of the fact that the tube and shaft axially coincide, while the former as it fits in an inclined recess in the face of the wheel must therefore, have its axis at an angle to the axis of such 20 wheel. The shaft 27 journaled in said bushings 23 and 25, and, where it engages the outer one, is preferably of tapered form as shown at 27^a. The outer end of said shaft is threaded and is equipped with a 25 cap 28 fitting around the outer end of the tubular arm 22. It is also provided with a clamping nut 29 for clamping a grinding wheel 30 on the shaft against cap 28. An internally threaded sleeve 31 is screwed up 30 on the inner end of the shaft 27, and screwed into said sleeve and abutting the inner end of said shaft is a plug 32 equipped with a rectangular bore or passage for the reception of the angular outer end of a resilient or flexible shaft 33 extending through 35 the mandrel 4 and rigidly secured to a chuck 34 of any suitable type to which rotation may be imparted. As shown, the chuck 34 is adapted to be driven by a belt 40 at a very high rate of speed, the transmission of power being through said resilient shaft and shaft 27 to the grinding wheel 30. The chuck is mounted in a tapering sleeve 35 adapted to be secured within the 45 mandrel in a common and well known manner, the arrangement being such that the shaft 33 shall be free to bow or bend slightly without interfering with its rotation, in order to accommodate different 50 adjustments of the tubular arm 22 for the purpose of grinding cylinders of different diameters.

By reference to Figure 4, it will be seen that the arm 22 is shown in full lines 55 in one position and in dotted lines in a different position, this change of position being due to adjustment effected by the operation of the worm and the rotation imparted thereby to the worm wheel upon the pitched 60 or inclined face 11 of plate 8.

In operation the power transmitted to the mandrel effects rotation of plate 8 around its own axis, this resulting in causing turning movement at the same speed 65 to the worm wheel, but as said wheel is

disposed out of perpendicular with respect to the axis of said plate, the grinding wheel is caused to travel bodily in a circle. At the same time the rapid rotation imparted to the flexible shaft 33, imparts a corresponding rotation to the grinding wheel around its own axis, the said shaft weaving or bending to accommodate the angular relation thereto of the shaft 27. By the arrangement described it will be apparent 75 that an efficient grinding action is obtained and that through the adjustment of the worm wheel explained, the circle described by the grinding wheel can be made larger or smaller within the limit of the device, 80 the pitch of the face 11 of plate 8 determining the angular relation of the axis of shaft 27 with respect to the axis of shaft 33.

From the above description it will be apparent that I have produced a grinding 85 attachment for lathes which embodies the features of advantage set forth as desirable in the statement of the object of the invention, and it is to be understood that while I have illustrated the preferred embodiment of the invention, it is susceptible 90 of modification in various particulars without departing from the principle of construction and mode of operation involved.

What I claim is:

1. The combination of a rotatable plate, a wheel rotatable with said plate and having its axis permanently fixed at an angle to the axis of said plate, a shaft movable with and bearing a journaled relation to 100 said wheel and disposed with its axis at an angle to the axis of the wheel, a grinding wheel on said shaft, and a flexible shaft coupled to revolve said first-named shaft around its own axis. 105

2. The combination of a rotatable plate, a wheel carried by said plate and having its axis permanently fixed at an angle to the axis of the plate, an arm projecting from said wheel and having its axis at an angle to the axis thereof, a shaft journaled in said arm and axially aligned therewith, a grinding wheel on the outer end of said shaft, and a flexible shaft extending through 110 said plate and coupled to the inner end of 115 the first-named shaft.

3. The combination of a rotatable plate, a worm wheel rotatable with and journaled on said plate and bearing a pitched relation thereto, a worm shaft for rotatably 120 adjusting the said wheel in its pitched relation to the face of said plate, a shaft movable with and having its axis at an angle to the axis of said wheel and independently rotatable around its own axis, 125 and a grinding wheel secured on said shaft.

4. The combination of a rotatable plate, a worm wheel rotatable with and journaled on said plate and bearing a pitched relation thereto, a worm shaft for rotatably 130

- adjusting the said wheel in its pitched relation to the face of said plate, a shaft movable with and having its axis at an angle to the axis of said wheel and independently rotatable around its own axis, and a flexible shaft coupled to the first-named shaft.
5. The combination of a rotatable mandrel, a plate thereon having an inclined face, a rotatably-adjustable wheel journaled on the plate and fitted against the inclined face thereof, a flexible shaft extending through the mandrel and said plate and wheel, a tubular arm carried by and disposed with its axis at an angle to the axis of said wheel, a shaft journaled in the said arm and coupled to the first-named shaft, and a grinding wheel secured on the shaft journaled in the arm.
10. 6. The combination of a rotatable plate, a wheel rotatable with said plate and having its axis permanently fixed at an angle to the axis of said plate, a shaft movable with and bearing a journaled relation to said wheel and disposed with its axis at an angle to the axis of said wheel, and means for revolving said shaft around its own axis.
15. 7. The combination of a rotatable plate, a wheel carried by said plate and having its axis permanently fixed at an angle to the axis of the plate, an arm projecting from said wheel and having its axis at an angle to the axis of said wheel, a shaft journaled in said arm and axially alined therewith,
- and a flexible shaft extending through said plate and coupled to the inner end of said first-named shaft.
8. The combination of a rotatable plate, a worm wheel rotatable with and journaled on said plate and having a pitched relation thereto, a worm shaft for rotatably adjusting the said wheel on said plate, a shaft movable with and bearing a journaled relation to said wheel and having its axis at an angle to the axis thereof, and means for 45 rotating said shaft around its own axis.
9. The combination with a rotatable plate having an inclined face, a rotatably-adjustable wheel journaled on said plate and fitted against the inclined face thereof, a shaft 50 journaled in said wheel and having its axis at an angle to the axis thereof, means for rotatably adjusting said wheel with respect to said plate, means for rotating said plate, and means for rotating said shaft.
10. The combination with a rotatable plate having an inclined face, a rotatably-adjustable wheel journaled on said plate and fitted against the inclined face thereof, a shaft journaled in said wheel and having its axis at an angle to the axis thereof, a worm for rotatably adjusting said wheel with respect to said plate, means for rotating said plate, and means for rotating said shaft.

In witness whereof I hereunto affix my signature.

WILLIAM A. JENNINGS.
